UNITED STATES PATENT OFFICE.

JOHN HARBOLSHEIMER, OF PHILADELPHIA, PENNSYLVANIA.

MATCH-SAFE.

No. 911,495.

Specification of Letters Patent.

Patented Feb. 2, 1909.

Application filed August 17, 1908. Serial No. 448,770.

To all whom it may concern:

Be it known that I, JOHN HARBOLSHEIMER, a citizen of the United States, residing at Philadelphia, in the county of Philadelphia and State of Pennsylvania, have invented 5 certain new and useful Improvements in Match-Safes, of which the following is a specification.

My invention relates to match safes or 10 holders and particularly to those match safes which are adapted to be fastened to a wall and to provide separate compartments for used and unused matches, the object of my invention being to provide a match safe 15 of exceedingly simple construction, very simply made and wherein the parts cannot become detached through use or liable to break off.

The invention consists in the details of 20 construction set forth in the accompanying specification and particularly stated in the claims.

In the drawings Figure 1, is a perspective view of my match safe. Fig. 2, is a trans- 25 verse section on the line 2-2 of Fig. 1. Fig. 3, is a longitudinal section. Fig. 4, is a detail of a compartment detached. Fig. 5, is an enlarged fragmentary section. Fig. 6, is a detail of a modification.

30 A designates the back plate of relatively thin metal having the margins thereof turned over upon the plate as at a, so as to provide a strengthening bead around the margins, and at the same time hold the compartments in place as will be later described. The compartments are triangular in cross section composed of a front plate B the ends of which are turned at right angles as at B' to form the sides of the compartment. The 35 rear edges of these sides are flanged outwardly as at b, these flanges being adapted to be inserted beneath the side flanges a of the back plate A. The upper edge of the compartment is turned over and downward 40 upon the metal of the compartment so as to strengthen the edge and to also form a rounded edge which will not cut the hand. The lower edge of the front is extended downward as at b' and is adapted to enter a slot A' in the back plate. The lowermost 45 compartment is made in precisely the same manner as the uppermost, but the lower edge thereof b² is inserted under the over-turned edge a' which corresponds with the 50 overturned side edges a. The lowermost compartment is made in precisely the same manner as the uppermost, but the lower edge thereof b² is inserted under the over-turned edge a' which corresponds with the 55 overturned side edges a.

As above stated the plate A is transversely

slotted as at A', and just below this slot is a transverse corrugation A² which is depressed outwardly from the back of the plate. The lower edge b' of the uppermost 60 compartment B is adapted to be passed through the slot and be pressed inward into this corrugation. This prevents the compartment from being forced downward out of its proper position, and at the same time 65 acts to prevent the compartment from being accidentally forced upward out of position. I have found by experiment that the corrugation is sufficient for this purpose.

In order to prevent the forcing inward of 70 the sides of the compartment, I provide longitudinally extending corrugations C on either side of plate A just inward of the beads a. When the compartments are inserted in the side and forced down in position on the back plate, these corrugations C will come just inside of the inner face of the side walls of the compartment and will prevent the sides of the compartment being forced inward and thus out of engagement 75 with the turned over edges a. A strip of sand paper E may be also supported at its side edges beneath the turned over edges of the plate A and it will be seen that the uppermost corrugation A² which holds the upper compartment in place will prevent the upward shifting of the sand paper, while to prevent any downward shifting of the paper I provide the lower transverse corrugation A³. In place of the sand paper it is ob- 80 vious that I might corrugate the rear plate in the space between the two compartments or form it with rows of projections to form a surface against which the matches may be struck as shown in Fig. 6. 85

90 After the compartments have been inserted in place and the sand paper placed beneath the side flanges, if any sand paper is used, I preferably bend the side edges outward at a slight angle as shown in Fig. 3. 100 This clenches the compartments and acts to prevent any movement of them. 95

As will be seen my match safe is very 105 simply made, has no parts which project through the metal and are therefore liable to be broken off, nor are the parts soldered together. For this reason, matches which are still burning may be thrown into the waste compartment without danger.

A further advantage lies in the rigidity 110 with which the compartments are held to the back plate. Thus no matches can slide or

work downward out of the compartment or through the joint at the sides. This is liable to occur when the compartments are joined to the back plate by ears or tabs inserted 5 through slits which easily become loose or break off thus loosening the joints between the material of the compartment and the back plate.

Having thus described my invention what 10 I claim as new and desire to secure by Letters Patent is:

1. In a match safe, a back plate having inwardly turned over edges and compartments having a downwardly and inwardly 15 inclined front and sides formed with outwardly turned flanges along their edges adapted to be inserted and held beneath said turned over edges of the back plate, said back plate having outwardly projecting longitudinal corrugations on opposite sides located just inside of the inner face of the side plates of the compartments.

2. In a match safe, a back plate having turned over side edges and a turned over 25 bottom edge, compartments having laterally projecting flanges on their edges adapted to be inserted and held beneath said turned over edges of the back plate, each compartment having a downwardly projecting flange 30 at its lower edge, the back plate being provided with a slot through which the downwardly projecting flange of a compartment may pass.

3. In a match safe, a back plate having 35 laterally turned over edges, a compartment having a downwardly and inwardly inclined front and sides formed with laterally projecting flanges adapted to be inserted be-

neath and held in said turned over edges of the back plate, the lower edge of said compartment being provided with a downwardly projecting flange, said back plate having a transverse slot through which said lower edge flange projects, and an outwardly extending corrugation in said back plate 45 into which the edge of said flange is inserted.

4. In a match safe, a back plate having inwardly bent side edges, compartments having outwardly extending lateral flanges inserted beneath said inwardly bent side edges of the back plate and held thereby, said side edges and compartment flanges being turned 50 at an angle to the back plate.

5. In a match safe, a back plate having 55 inwardly bent side edges, compartments one above the other having sides provided with laterally extending flanges inserted and held within said side edges of said back plate, a transverse corrugation in the back 60 plate against which the lower edge of the uppermost compartment contacts to hold the same in place, an inwardly bent edge on the lower end of the back plate into which the flange on the lower end of the lowermost 65 compartment extends to hold it in position, and a roughened match striking portion between the two compartments.

In testimony whereof I have signed my name to this specification in the presence of 70 two subscribing witnesses.

JOHN HARBOLSHEIMER.
